UNITED STATES PATENT OFFICE.

ALLISON AKIN, OF EAST ORANGE, NEW JERSEY, ASSIGNOR, BY MESNE ASSIGNMENTS,
TO WESTERN ELECTRIC COMPANY, INCORPORATED, A CORPORATION OF NEW YORK.

TELEPHONE SYSTEM AND APPARATUS.

1,211,031.

Specification of Letters Patent.

Patented Jan. 2, 1917.

Application filed June 21, 1915. Serial No. 35,373.

To all whom it may concern:

Be it known that I, ALLISON AKIN, a citizen of the United States, residing at East Orange, in the county of Essex and State of New Jersey, have invented certain new and useful Improvements in Telephone Systems and Apparatus, of which the following is a full, clear, concise, and exact description.

This invention relates to telephone switching systems and apparatus therefor, and more particularly to a combined electromagnetic signal controlling relay and impedance coil for a bridged impedance type of link circuit.

The object of this invention in general is to produce a simple relay of economical form which may be connected in bridge of the strands of a cord circuit in series with the battery which supplies current to the transmitter at the way station, which will operate at high efficiency upon direct currents and will afford sufficient impedance to alternating currents of high frequencies to prevent the shunting of the voice currents.

In accordance with the general features of this invention, there is provided a relay having two windings connected with the strands of a cord, circuit and comprising a structure in which there are provided a plurality of magnetic paths of different lengths which prevent complete saturation of the core with a superposed direct current flowing through the windings. A form of relay embodying the characteristics required to make this invention successful is one in which the core, which is preferably of a larger cross-sectional area than the cross-sectional area of the armature, is formed of laminæ, which constitute with the armature a plurality of separate magnetic paths including air-gaps of different lengths. The armature of the relay is mounted to move in a direction transverse to the longitudinal axis of the core.

In the drawings illustrating this invention, Figure 1 is a diagram of a cord circuit and apparatus embodying the features of this invention; Fig. 2 is a view in side elevation of a relay made in accordance with this invention, and Fig. 3 is an end view of the relay.

As shown in Fig. 1, 5 and 6 designate subscribers' telephone lines terminating at one end in the usual subscribers' equipments 7 and 8, and at the other end in line jacks 9

and 10, and having connected with them the usual line and cutoff relays 11, 11 and 12, 12. A cord or link circuit comprising strands 16 and 17 divided by means of condensers 18 and 19 and having plugs 20 and 21 connected with its strands, is adapted to connect the two subscribers' lines by the insertion of the plugs 20 and 21 into the line jacks 9 and 10. A relay 24 having two windings 25 and 26 has these windings connected with the strands 17 and 16 respectively and in series with a grounded source of energy 27. This relay 24 controls a supervisory signal 28 and is actuated over a circuit including the line wires when the subscriber's receiver is removed from the switchhook.

The relay 24 is substantially the same mechanically as the relay shown and described in the Craft Patent 1,121,897 of December 22, 1914. The relay of this invention differs, however, from the relay shown in the Craft patent in that the core 30 thereof is made up of sheets 31, 31 of magnetic material which sheets are clamped together to form a core which is considerably larger in cross-sectional area than the armature 32. The armature 32, which is U-shaped, is mounted upon a rearward extension of the core 30 and is adapted to move in a direction transverse to the longitudinal axis of the core. By reason of this construction there are provided a plurality of separate magnetic circuits including the relay armature 32 and the separate laminæ, 90 each magnetic circuit having an air-gap different in length from the other depending upon the distance from the armature of the separate laminæ comprising the core. Due to the large cross-sectional area of the core 30 compared with that of the armature 32, and to the fact that there are a plurality of magnetic circuits each including an air-gap, the armature will pull up readily in response to energizing current in the windings, but the core 30 will not become entirely saturated. For example, when the armature is in attracted position, the lamina to which the armature is adjacent forms with the armature a magnetic path of low reluctance compared to the path including the armature, the outermost lamina and the intervening sections of the intermediate laminæ and associated non-magnetic gaps. Therefore, with a given number of ampere- 110

turns of magnetizing force produced by the relay winding, the portion of the core adjacent to the armature will have a much higher flux density than the most remote 5 portion or any intermediate portion. It follows then that enough magnetizing force to just saturate the armature and the adjacent portion of the core will not saturate the portions farther removed, which is 10 the case under service conditions. Another action also takes place in relays of this construction which has previously not advantageously been made use of in relay design, and that is the well-known 15 demagnetizing effect of "ends" in a magnetic circuit. Any magnetic path with non-magnetic gaps therein tends to oppose the flux flow and hence the degree of magnetization which a given magnetomotive 20 force can produce. In this invention this phenomenon is advantageously made use of to limit the degree of magnetization in the portions of the core removed from the armature; since, as has been hereinbefore 25 pointed out, the magnetic paths of which such portions form a part have non-magnetic gaps therein. Due to the fact then that a part of the core is unsaturated and therefore of high permeability to small high 30 frequency currents the relay gives satisfactory retardation effects at telephonic fre-

quencies, and the bridge containing this relay will be opaque to alternating currents of talking frequencies. A relay of this type can be easily produced at a slight cost, and 35 it has been determined that with such a relay in the cord circuit the transmission efficiency compares favorably with that of the standard repeating coil cord circuits.

What is claimed is:

1. A relay comprising an armature of magnetic material, a core, composed of superposed layers of magnetic and non-magnetic material at varying distances from said armature to provide magnetic paths of different lengths for increasing the difference in the magnetic density of the core at points near to and remote from the armature and an energizing winding for said core and armature. 40
2. In an electromagnetic device, a core composed of a plurality of laminæ separated by non-magnetic gaps, an armature of magnetic material in operative relation thereto and adapted to move toward the core in a direction transverse to the plane of said laminæ, whereby the core forms a plurality of magnetic paths of different lengths having non-magnetic gaps therein. 45

In witness whereof, I hereunto subscribe my name this 17 day of June A. D., 1915.

ALLISON AKIN.
